UNITED STATES PATENT OFFICE.

JOSEPH SYLVAN, OF CHICAGO, ILLINOIS.

VENTILATOR.

1,301,195.

Specification of Letters Patent.

Patented Apr. 22, 1919.

Application filed February 24, 1919. Serial No. 278,786.

To all whom it may concern:

Be it known that I, JOSEPH SYLVAN, a citizen of the United States, and a resident of Chicago, county of Cook, and State of Illinois, have invented certain new and useful Improvements in Ventilators; and I do hereby declare that the following is a full, clear, and exact description thereof, reference being had to the accompanying drawings, and to the letters of reference marked thereon, which form a part of this specification.

This invention relates to improvements in ventilators for roofs, skylights and the like and consists of the matters hereinafter described and more particularly pointed out in the appended claims.

The object of the invention is to provide a ventilator of the kind described, which is simple in construction and is efficient in operation for its intended purpose.

The advantages of the invention will appear as I proceed with my specification.

In the drawings:

Figure 1 represents a view in side elevation of a ventilator embodying my invention.

Fig. 2 represents a view in front end elevation of the same.

Fig. 3 represents a vertical section through the ventilator, the plane of the section being indicated by the line 3—3 of Fig. 2.

Fig. 4 represents a view in rear end elevation of the ventilator embodying my invention.

Fig. 5 represents, on an enlarged scale, a view partly in plan elevation and partly in horizontal section, the plane of the sectional part being indicated by the line 5—5 of Fig. 3.

Referring now in detail to that embodiment of the invention illustrated in the accompanying drawings:—10 indicates the upright, tubular sheet metal stem or base of the ventilator, which is attached in any suitable manner to a roof or skylight, and 11 indicates as a whole, the sheet metal top of the ventilator which is rotatably mounted on and surrounds the top part of the stem 10.

The top 11 comprises a head 12 and a hood 13. The head 12 includes a front, wind deflecting plate 14 and a rear wing plate 15. The front plate 14 is transversely rounded at its middle, concentric with the stem and its opposite sides are bent or flared out-

wardly and rearwardly, so that their rounded marginal parts 16 terminate in a plane a short distance to the rear of the vertical plane of the axis of the stem. The top end 17 of said front plate is curved or rounded 60 rearwardly and spreads laterally and terminates at the top edges of said marginal parts 16. The wing plate 15 of the head 12 is of a width approximating the diameter of the stem 10. The middle part 18 of said wing 65 plate is flared rearwardly and downwardly from the top edge of the front plate 14, while the sides 19 of said wing plate diverge forwardly and outwardly from said middle part to terminate in upright, laterally extending flanges 20. Said flanges are arranged in the plane of, but are spaced inwardly from, the edges of the rounded margins 16, in connection with which are defined rearwardly facing, spaced side openings 21, 70 21, one at each side of the wing plate 15. The bottom ends of said openings are closed by horizontal floor plates 21a. The bottom edges of the middle part 18 and of the sides 19 of the wing plate 17, define a mouth 80 22, which communicates with the top end of the stem 10.

The hood 13 consists of a sheet metal plate bent into a form somewhat like that of the wing plate 15 before referred to. The middle part 23 of said hood is arranged in a plane spaced from, but parallel with the middle part 18 of the wing plate 15, and the side parts 24 thereof are spaced from, but are parallel with the side parts 19 of said wing plates. The front edges of said side parts 24 are attached to the edges of the upright flanges 20 of the wing plates 15, so as to provide a channel or conduit 25 between the hood and said wing plate, which 90 has a discharge opening arranged in the plane of the mouth 22 of said wing plate. The upper end 26 of the said middle part 23 of the hood is curved upwardly and forwardly and terminates in a plane above that 100 of the head 12, the upper ends of the sides 24 of said hood, blending into upright walls 27, which extend from the rounded top end 17 of the head 12 to the upper end 26 of the hood 13, so as to define in connection with 105 said top end 17 an inlet mouth 28 which opens into the channel or conduit 25 (see Fig. 3). On the vertical median line of the hood 13 at its top is secured a vane 29.

Preferably the head 11 is rotatably mount- 110

ed on the stem 10, so that when wind pressure is exerted against the vane 29, the head will turn to present the inlet mouth 28 of the hood, forwardly or toward the direction 5 from which the wind is blowing, while the side mouths 21 will open rearwardly or in the direction toward which the wind is blowing. I rotatably attach the head 11 to the stem 10, as follows:

10 To the inner surface of the bottom edge of the front plate 14 is secured a spider ring 30 having radial arms, the ring surrounding the top end of the stem 10. Vertically above said ring is attached a second 15 spider arm member 31 and within the stem 10 are top and bottom spider rings 32 and 33, also having radial arms. A bolt or pivot pin 34 passes through the center of the spider arms, so as to hold the top 11 on the stem 10, and between the arms of the rings 20 30 and 32 is provided an antifriction bearing 35 (see Fig. 3).

The operation of the improved ventilator is as follows:—Assume that the wind is blowing and has engaged the vane 29 to rotate the top 11 on the stem 10 so as to present the mouth 28 to the wind. Such wind as enters the mouth 28 will pass down through the channel or conduit 25 (as shown in Fig. 30 3) and set up an aspirating action in the vicinity of the mouth 22 to establish a suction action above the top end of the stem 10 at its center. Such wind as impinges against the rounded middle part of the front plate 35 14 will be deflected laterally by the sides of said plate so that as it passes the rounded margins 16 of the said plate 14, it will produce an aspirating action in the rearwardly facing side mouths 21 and establish a suction above the top end of the stem 10 40 at its sides (as shown in Fig. 5). The combined area of the side openings 21 approximates the area of the stem, and thus the suction produced by said mouths when considered in connection with the suction exerted through the bottom mouth 22, insures ample ventilation in the room of the building, to the roof or skylight of which the ventilator is attached.

50 Should the wind shift to a direction at right angles to that in which it was originally blowing, it will, through the vane, rotate the head 11 to present the mouth openings in the proper direction, and thus 55 no air will enter the mouths 21, and 22 and produce a down-draft in the ventilator. Furthermore, no snow or rain can enter the stem 10 by reason of the construction before described. Should snow or rain enter the 60 mouth 28, it will be discharged through the bottom end of the channel or conduit 25 without the ventilator. The parts are easy to make and when assembled provide a balanced construction which will rotate about the pivot bolt 34 without binding. The ven-

tilator readily withstands high wind pressure because the parts are so arranged as to brace one another.

While in describing the invention, I have referred to certain details of mechanical 70 construction and arrangement of parts, I do not wish to be limited thereto, except as may be pointed out in the appended claims.

I claim as my invention:

1. A ventilator for roofs, skylights and 75 the like, comprising an upright, tubular stem, a top mounted on said stem and consisting of a head and a hood, the head being formed to provide laterally spaced, rearwardly facing, upright side openings and a 80 rearwardly and downwardly facing mouth between said side openings, all of which communicate directly with said stem, and said hood providing a conduit having an inlet opening forwardly above the head and an outlet opening at the bottom of said head.

2. A ventilator for roofs, skylights and the like, comprising an upright, tubular stem, a top mounted on said stem and consisting of a head and a hood, the head being 90 formed to provide laterally spaced, rearwardly facing, upright side openings and a rearwardly and downwardly facing mouth between said side openings, all of which communicate directly with said stem, and said hood providing a channel about the sides and rear of said head, which has an inlet opening forwardly above the head and an outlet opening at the bottom of said head.

3. A ventilator for roofs, skylights and the like, comprising an upright, tubular stem and a top rotatively mounted thereon, said top consisting of a head and a hood, the head being formed to provide laterally spaced, rearwardly facing, upright side openings and a rearwardly and downwardly facing mouth between said side openings, all of which communicate directly with said stem, and said hood providing a conduit having 105 an inlet opening forwardly above the head and an outlet opening at the bottom of said head.

4. A ventilator for roofs, skylights and the like, comprising an upright, tubular 115 stem and a top rotatively mounted thereon, said top consisting of a head and a hood, the head being formed to provide laterally spaced, rearwardly facing, upright side openings and a rearwardly and downwardly facing mouth between said side openings, all of which communicate directly with said stem, and said head providing a channel about the sides and rear of said head which has an inlet opening forwardly above the 120 head and an outlet opening at the bottom of said head.

5. A ventilator for roofs, skylights and the like, comprising an upright, tubular stem and a top rotatively mounted thereon, 125

- said top including a head and a hood, the head consisting of a rear wing plate and an upright front plate having a transversely rounded middle part, a rounded top part 5 and outwardly and rearwardly extending side parts, said wing plate defining a downwardly facing mouth which opens into the stem and the side margins of said wing plate together with the side margins of said 10 front plate, defining upright, laterally spaced, rearwardly facing side openings which also open into the stem, said hood providing a channel about said wing plate between said side openings, which channel has 15 an air inlet mouth above the rounded top part of the head and a discharge mouth arranged in the plane of the bottom mouth of said head.
6. A ventilator for roofs, skylights and 20 the like, comprising an upright, tubular stem and a top rotatively mounted thereon, said top including a head and a hood, the head consisting of a rear wing plate and an upright front plate having a transversely

rounded middle part, a rounded top part 25 and outwardly and rearwardly extending side parts, said wing plate defining a downwardly facing mouth which opens into the stem and the side margins of said wing plate together with the side margins of 30 said front plate, defining upright, laterally spaced, rearwardly facing side openings which also open into the stem, said hood providing a channel about said wing plate between said side openings, which conduit 35 has an air inlet mouth above the rounded top part of the head, and a discharge mouth arranged in the plane of the bottom mouth of 40 said head, and a vane fixed to the hood on its vertical, median line.

In testimony that I claim the foregoing as my invention, I affix my signature in the presence of two witnesses, this 19th day of February, A. D., 1919.

JOSEPH SYLVAN.
